UNITED STATES PATENT OFFICE.

JOHN EDWARD OGDEN, OF CORNWALL, NEW YORK.

FOLDED METAL EXPANSION-SHIELD.

1,350,562.

Specification of Letters Patent. Patented Aug. 24, 1920.

Application filed March 29, 1919. Serial No. 286,146.

To all whom it may concern:

Be it known that I, JOHN EDWARD OGDEN, a citizen of the United States of America, and a resident of Mountainville, town of 5 Cornwall, Orange county, and State of New York, have invented certain new and useful Improvements in Folded Metal Expansion-Shields, of which the following is a specification, reference being had to the accom-

10 panying drawings, forming a part thereof.

My invention relates to improvements in expansion shields and its object is to provide a simple and inexpensive device for use as a bolt anchor for securing a bolt or screw 15 to structures of cement, brick or other material with which the threads of the bolt or screw will not engage effectively, and to provide a method of making such a device of sheet metal.

20 In order that my invention may be thoroughly understood, I will now proceed to describe the same in the following specification, and will then point out the novel features thereof in appended claims.

25 Referring to the drawings:

Figure 1 is an elevation of a blank of sheet metal which is rolled to make an expansion shield.

Fig. 2 is an edge view of the same blank.

30 Fig. 3 is an elevation of the shield made of the blank shown in the preceding figure.

Fig. 4 is an elevation of a modified form 35 of blank.

Fig. 5 is an elevation of the shield made of the blank shown in Fig. 4.

Fig. 6 is an elevation of a blank of modified form which is shown in Fig. 7, rolled into a shield.

40 Fig. 8 is an elevation of another form of blank which may be used in carrying out my invention.

Fig. 9 is a sectional elevation of a portion of a wall with a hole drilled therein and with an expansion shield or bolt anchor 45 of the form shown in Fig. 7, shown driven therein. The end portion of a lag screw started into the shield is shown in elevation in this figure.

In Fig. 1, 10 designates the upper edge of 50 the blank and 11 its lower edge, which is substantially twice as long as the upper edge. 12 is a side edge of this blank which is substantially perpendicular to its upper and lower edges, and 13 is the other edge which 55 thus completes an undivided blank. Accord-

ing to the method herein disclosed, this blank is first cut out of sheet metal. Then all but the upper part of its surface is corrugated on diagonal lines as shown at 14 spaced equally apart at a distance equal to 60 the pitch of the screw which is to be used with the finished shield. These corrugations may increase in depth toward the lower edge of the blank as shown in Fig. 2.

This blank is rolled around an axis which 65 is to be the center of the tubular shield, to form the structure shown in Fig. 3. The length of the upper side 10 is substantially equal to the periphery of the upper end of the tube thus formed, but as the other parts 70 of the blank are wider than this upper edge, the metal will be wrapped around itself below this upper edge to an increasing extent to the lower edge of the tube. With this particular form of structure it is desirable 75 to have the outside of the tube cylindrical, but as the walls thereof are thicker at the lower end of the tube on account of the excess of metal provided by the wide bottom 80 11 of the blank, it is desirable to have the bore of the shield or tube tapered.

The blank shown in Fig. 4 has its upper part 15 of a width about equal the periphery of the tube into which it is to be rolled so that the edges 16, 16 of this part will abut 85 when the tube is formed, as shown in Fig. 5. The rest of the sides flare to the lower edge which is much wider than the upper edge so that excess of metal is provided as in the other case near the lower end of the 90 shield. This form of blank is also corrugated and then wound into a tube with a tapered bore and a substantially cylindrical exterior.

The blank shown in Fig. 6 has both its 95 upper and lower edges 20 and 21 of about the same width and about equal to the periphery of the shield which it is to form. The side 22 is perpendicular to these edges, but in this case the widest part of the blank is 100 between the side 22 and a point 23 intermediate the upper and lower edges.

This form of blank may be wound into a tube with a non-tapered or cylindrical bore as shown in Fig. 7, the outside diameters 105 of the ends of which will be equal but the outside of which will taper from both ends to the part where the point 23 lies where there is the greatest excess of metal.

The blank shown in Fig. 8 will form a 110

similar shield to that shown in Fig. 7 except that the upper part 24 thereof will not overlap and as both of its sides flare instead of but one of them, the overlapped metal 5 will lie some on the inside of the tube and some on the outside. But in either case the result is to thicken the walls of the tube at desired parts thereof.

The way this device is used as a bolt 10 anchorage is shown in Fig. 9. A hole of proper size to receive the shield is drilled in a wall 30, and the shield placed therein. If the shield has a tapered bore and cylindrical outside, it may fit the hole readily. 15 The corrugations are so disposed as to lie in helical lines and are arranged to receive the threads of a device such as a lag screw 31. As the screw is forced in, the shield is expanded and the excess metal at the part 20 of the shield where the bore is restricted becomes tightly crowded between the lag screw and the wall of the hole and thus effectively holds the screw.

While it is desirable for the effective operation of this device that the bore be restricted at some part of the length of the shield when it is ready to receive the lag screw or other device, it is not necessary that the restriction of the bore be made when 25 the device is manufactured. In connection with Figs. 6, 7 and 8, I have shown and described shields with non-tapered or cylindrical bores. These have however, excess metal about certain parts of their length. 30 A shield which was of this form is shown in Fig. 9, driven into the hole in wall 30. The act of forcing it into the hole causes the shell to be forced inwardly so that its bore is tapered or restricted as shown at 32. 35 Screwing the bolt in forces this restricted part outwardly again to form a secure anchorage in the manner previously described.

The corrugations shown are not needed when the blank of which the shields are made are of soft metal.

40 I believe that many kinds of expansion shields can be made according to the novel method herein set forth, and have illustrated a number of forms of shields, which embody 45 the invention in order to show that I do not intend any limitations other than those imposed by the appended claims.

What I claim is:

1. An expansion shield formed of a blank 50 of sheet metal having a smaller transverse dimension at one end than at other parts thereof, rolled around a central axis into a tube with the metal wrapped around itself to an increased extent at points away from 55 the end of smaller transverse dimension, the inside of said tube being constructed to be engaged by the threads of a bolt.

2. An expansion shield formed of a blank 60 of sheet metal having a smaller transverse dimension at one end than at other parts 65

thereof, said blank being corrugated and rolled around a central axis into a tube with the metal wrapped around itself to an increased extent at points away from the end of smaller transverse dimension.

3. An expansion shield formed of a blank 70 of sheet metal having a smaller transverse dimension at one end than at other parts thereof, said blank being corrugated and rolled around a central axis into a tube with the metal wrapped around itself to an increased extent at points away from the end of smaller transverse dimension with the corrugations so disposed as to lie helically 75 in the tube.

4. An expansion shield formed of a blank 80 of sheet metal having a smaller transverse dimension at one end than at other parts thereof, said blank being corrugated and rolled around a central axis into a tube with the metal wrapped around itself to an increased extent at points away from the end of smaller transverse dimension with the corrugations increasing in depth away from 85 said end of smaller transverse dimension and so disposed as to lie helically in the tube.

5. An expansion shield formed of a blank 90 of sheet metal having a smaller transverse dimension at one end than at other parts thereof, rolled around a central axis into a tube formed to receive the threads of a bolt, a part of the bore of said tube being arranged to be restricted in at least one of its transverse dimensions before a bolt is 95 inserted therein, and the metal of said blank being wrapped around itself near the part 100 of the shield having the restricted bore.

6. An expansion shield formed of a blank 105 of sheet metal having a smaller transverse dimension at one end than at other parts thereof, rolled around a central axis into a tube with a tapered bore, with the metal wrapped around itself to an increased extent near the part of the device where the bore 110 is tapered, the inside of said tube being constructed to be engaged by the threads of a bolt.

7. An expansion shield formed of a blank 115 of sheet metal having a part at one end of a predetermined width and other parts thereof wider, rolled around a central axis into a tube having a circumference approximately equal 120 said predetermined width, with the metal of the wider parts of the blank wrapped around itself to increase the thickness of the walls of the tube, the inside of said tube being constructed to be engaged by the threads of a bolt.

8. An expansion shield formed of a blank 125 of sheet metal having a part at one end of a predetermined width and other parts thereof wider, said blank being corrugated and rolled around a central axis into a tube having a circumference approximately equal 130

said predetermined width, with the metal of the wider parts of the blank wrapped around itself to increase the thickness of the walls of the tube.

5 9. An expansion shield formed of a blank of sheet metal having a part at one end of a predetermined width and other parts thereof wider, said blank being corrugated and rolled around a central axis into a tube having a circumference approximately equal 45
10 said predetermined width, with the metal of the wider parts of the blank wrapped around itself to increase the thickness of the walls of the tube, with the corrugations so disposed as to lie helically in the tube. 50

10 10. An expansion shield formed of a blank of sheet metal having a part at one end of a predetermined width and other 55
20 parts of the blank flaring to greater widths, rolled around a central axis into a tapered tube with the circumference of the tube at the larger end of the bore approximately equal said predetermined width with the 60
25 metal of the wider parts of the blank wrapped around itself to progressively increase the thickness of the walls of the tube as the size of the bore decreases.

11. An expansion shield formed of a blank of sheet metal having a part at one end of a predetermined width and other 65
30 parts of the blank flaring to greater widths, said blank being corrugated, rolled around a central axis into a tapered tube with the 70
35 circumference of the tube at the larger end of the bore approximately equal said predetermined width with the metal of the wider parts of the blank wrapped around itself to progressively increase the thickness 75
40 of the walls of the tube as the size of the

bore decreases, with the corrugations so disposed as to lie helically in the tube.

12. The herein described method of forming an expansion shield which comprises cutting out a blank of sheet metal with a smaller transverse dimension at one end than at other parts thereof, rolling said blank around a central axis into a tube and wrapping some of the metal around itself to an increased extent at points away from the end of smaller transverse dimension. 50

13. The herein described method of forming an expansion shield which comprises cutting out a blank of sheet metal with a smaller transverse dimension at one end than at other parts thereof, corrugating the metal, rolling said blank around a central axis into a tube and wrapping some of the metal around itself to an increased extent at points away from the end of smaller transverse dimension. 55

14. The herein described method of forming an expansion shield which comprises cutting out a blank of sheet metal with a smaller transverse dimension at one end than at the other parts thereof, corrugating the metal rolling said blank around a central axis into a tapered tube with the part of the blank of smaller transverse dimension forming the larger part of the bore of said tube and wrapping the wider parts of the metal around the tube to progressively increase the thickness of the walls of the tube around the part thereof where the size of the bore decreases. 60

In witness whereof I have hereunto set my hand this 10th day of February, 1919.

J. EWD. OGDEN.

Witness:

I. B. MOORE.
